SAFETY HELMET

William R. Bohner, Reading, and Jack N. Simpson, Wilshire, Pa., assignors to ESB Incorporated, a corporation of Delaware

Filed June 19, 1969, Ser. No. 17,772

Term of patent 14 years

Int. Cl. D2—05

U.S. Cl. D2—231

FIG. 1

FIG. 2

FIG. 3

FIG.4

FIG.5

FIG. 1 is a side perspective view of a safety helmet, showing our new design;

FIG. 2 is a cross sectional view thereof taken on the line 2—2 of FIG. 4;

FIG. 3 is a cross sectional view taken on the line 3—3 of FIG. 2;

FIG. 4 is a bottom plan view of the safety helmet; and FIG. 5 is a back elevational view thereof.

We claim:

The ornamental design for a safety helmet, as shown.
